(57) **CLAIM**

The ornamental design for a wrench socket for sprinkler head, as shown.

DESCRIPTION

FIG. 1 is a front elevational view of a wrench socket for sprinkler head showing my new design;

FIG. 2 is a rear elevational view thereof;

FIG. 3 is a left side elevational view thereof;

FIG. 4 is a top plan view thereof;

FIG. 5 is a bottom plan view thereof;

FIG. 6 is a cross-sectional view thereof taken along the line 6-6 shown in FIG. 1;

FIG. 7 is a front, bottom, and right perspective view; and,

FIG. 8 is a front, top, and right perspective view thereof.
